227,258

CARD READING KEYBOARD TERMINAL OR THE LIKE

Charles T. Inatomi, 10733 Flaxton St.,
Culver City, Calif. 90230

Filed Oct. 20, 1971, Ser. No. 191,133

Term of patent 14 years

Int. Cl. D14—02

U.S. Cl. D26—5 C

Fig. 1

Fig. 2

Fig. 3

Fig. 4

Fig. 5

FIG. 1 is a perspective view of a card reading keyboard terminal or the like embodying my new design;

FIG. 2 is a left side elevational view thereof, the right side being a mirror image of the side shown;

FIG. 3 is a top elevational view thereof;

FIG. 4 is a rear elevational view thereof; and

FIG. 5 is a bottom elevational view thereof.

I claim:

The ornamental design for a card reading keyboard terminal or the like, substantially as shown and described.
